UNITED STATES PATENT OFFICE.

ARTHUR E. HOWELL, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed February 27, 1920. Serial No. 361,783.

To all whom it may concern:

Be it known that I, ARTHUR E. HOWELL, a citizen of the United States, residing in Brooklyn Borough, in the county of Kings, 5 city and State of New York, have invented certain new and useful Improvements in Typewriting Machines, of which the following is a specification.

This invention relates to typewriting machines, and is herein disclosed as applied to an Underwood standard typewriting machine adapted to write leaders or rows of dots, stars, dashes or underlining characters, without the necessity of separately and manually actuating the proper key-lever for each dot or dash or other character of the row.

According to the present invention, the usual key or keys for typing the desired character may be actuated as usual in ordinary writing; but, when it is desired to write a leader or row of the characters, a finger-piece may be depressed to make effective connections which will operate the desired leader-type by any suitable source of power.

As herein disclosed, the usual key-levers of the typewriting machine which are used to type these characters may be provided with tails or devices, which are normally out of the way of power-driven actuating members, but which may be selectively operated by said members through the source of power. In the form of the invention herein illustrated, the source of power is shown as a shaft, comprising star-wheels forming the operating members for the key-levers and which are normally clear of the type-bars, but adapted to be shifted so that, at the rotation of the shaft, the desired key-lever will be actuated. The shaft is herein illustrated as driven by a hand-driven crank.

Instead of having a separate star-wheel for each of the key-levers, if it is desired to actuate in this manner, a single star-wheel may be adapted to be shifted to any one of a plurality of positions, to selectively actuate different key-levers. For determining which key-lever shall be thus actuated, there may be provided a plurality of finger-pieces

or push-keys, which are adapted to shift the star-wheels or members, the connections being such that, when a wheel or member is shifted, it remains shifted until the push-key which shifted it is returned to normal 55 position.

Instead of having a separate latch for each of the star-wheel-shifting keys, each shifting key may shift its wheel by a cam, comprising a dwell at the end, with the result that when the cam has once shifted the wheel, the wheel remains in its shifted position until a returning finger-piece, common to all of said shifting keys, is actuated and returns the actuated one to normal position. 60 65

Other features and advantages will hereinafter appear.

In the accompanying drawings,

Figure 1 is a sectional side view of an Underwood standard typewriting machine, 70 showing the present invention as applied thereto.

Figure 2 is a fragmentary plan view of parts of the machine, illustrating the character-printing key-levers which are actuated 75 in the manner described, and the connections for actuating them.

Figure 3 is a fragmentary view of part of Figure 2, but showing the star-wheel for the "6" or underscoring-key shifted to effective position. 80

Figure 4 is a similar view of the star-key or dash-key.

Figure 5 is a similar view of the period-key. 85

Figure 6 is a skeleton perspective, showing the principal parts of the present disclosure of the invention.

Figure 7 is an enlarged perspective view of the cam for setting a star-wheel to actuate either the star-key or the period-key. 90

In the Underwood standard typewriting machine, character keys, including the "6" key 10, the hyphen or star-key 11, the period-key 12, and other character keys 13, 95 when depressed, carry down their respective key-levers 14, to swing bell-crank sub-levers 15, thereby rocking type-bars 16 upwardly and rearwardly, so that lower-case type 17 or upper-case type 18 print upon the platen 19. 100

The platen, as usual, is journaled in a shift-frame 20, which forms part of a traveling carriage 21, the carriage running on rails 22 and 23, and the shift-frame being supported in the carriage, in part, by a shift-rail 24, forming the front of a usual rocking shift-frame 25.

Whenever a type-bar 16 approaches the platen 19, a heel 26 on it strikes a segmental universal bar 27, carrying it rearwardly to actuate the usual dogs 28, which control the carriage, by the escapement-wheel 29 in the usual manner.

If it is desired to actuate the hyphen-key 11, to write a leader or row of hyphens, a hyphen-shifting-key 30 may be pressed rearwardly until the typist's finger is flush with the front of a front plate 31, fast to the typewriter frame 32. When the hyphen-shifting-key 30 is thus pressed rearwardly, its stem 33 rocks rearwardly a rock-arm 34, fast upon a rock-shaft 35, which is journaled in the brackets 36 fast to the machine frame, thereby causing a rock-arm 37 on said shaft 25 to slide a star-wheel 38 along its shaft 39, it being slidably splined thereon by a key 40. This carries the star-wheel 38 above a C-shaped arm 41, fast to and depending from the lever 41^a of the hyphen-key, so that a roller 42 on said arm rests in the depression 43 between two teeth of the star-wheel. Turning the shaft 39 then causes the roller 42 to ride up on the faces of the teeth 44 of the star-wheel, one after another, thereby drawing downward the C-shaped arm 41 repeatedly, to actuate its key-lever 41^a precisely as if it were actuated by the touch of the typist's finger. The faces of the teeth 44 thus play the part of operating cams.

For turning the shaft 39, there may be provided upon it a spur-pinion 45, meshing with an idle pinion 46, which, in turn, meshes with a driving pinion 47, herein shown as fast to a hand-crank 48, journaled upon a stub-shaft 49 on the side of the machine frame, near enough the front of the machine to be conveniently reached and actuated.

The star-wheel 38 remains in engagement 50 with the roller 42, because the shifting connections are so provided as to effect this result. For this purpose, the connections for shifting the star-wheel 38 include a cam-member 50, pivotally attached to the rock-arm 37, by a shouldered screw 51, said cam-member comprising an opening or fork 52 in an extension which straddles the shaft 39, with the result that the cam-member 50 slides substantially forward and backward.

When the hyphen-shifting-key 30 was depressed, the cam-member 50 was drawn forward, so that the cam-face 53 thereon, engaging the hub 54 of its star-wheel, cammed said star-wheel to the right against the tension of the spring 55, which encircles

the shaft 39 and constantly tends to shift its star-wheel to the left clear of its C-shaped arm. The camming-member 50 remained in its shifted position, because a dwell or shoulder 56 of the cam bore against an adjacent end of the hub 54, thus making it impossible for the spring 55 to return the cam-member 50. To keep the cam-member 50 from being pressed to the left when it compresses the spring 55, the shaft 39 is provided with a collar 57 fast thereto and forming a bearing-member for the side of the cam-member 50.

After the typist has actuated the crank-handle 48 to print the desired number of hyphens, the hyphen-shifting-key 30 is returned to normal position, see Figures 1, 2, and 6, by depressing a finger-piece 58, which is formed as a rock-arm fast upon a shaft 59, rockable in a bracket 60, fast to the frame of the typewriting machine. Depression of the finger-piece 58 rocks the bail 61 forwardly to its Figure 1 and Figure 6 position, it having been swung from that position when the hyphen-shifting-key was depressed. To enable the bail 61 to operate efficiently, it projects upwardly and forwardly adjacent a lug 62 on the rock-arm 34, which serves as a bearing surface for the bail 61. Depression of the finger-piece 58 swings the bail 61 forwardly and the rock-arm 34 forwardly, and rocks the shaft 35 to swing the rock-arm 37 rearwardly, thus carrying the cam-member 50 backwardly to the Figure 2 position, permitting the spring 55 to carry the star-wheel clear of its C-shaped member.

If it is desired to type a leader or row of periods, a period-shifting-key 63 may be pressed rearwardly to rock rearwardly a second rock-arm 64 fast upon the shaft 35, and, since the rock-arm 64 is shorter than the rock-arm 34, the travel of its key 63, before coming flush with the plate 31, produces a greater rotation of the shaft 35 and thereby shifts the cam-member 50 further forward, causing the cam 53 to slide the hub 54 to the Figure 4 position, and then slide it further to the Figure 5 position, in which position the second cam-face 65 on the cam-member 50 has shifted the hub 54 to the right far enough to bring the star-wheel 38 above a C-shaped member 66, which is fast to and depends from the key-lever 67 of the period-key 12. The cam-member 50 is held in this position, because a second dwell 68 on it is brought against the hub 54 to the Figure 5 position.

To print a period in most typewriting machines, it is necessary to actuate the case-shift-key 69, to lift the platen so that the upper-case characters are effective to print. The typist, therefore, to print periods, depresses the case-shift-key 69, and then turns the handle 48, after having pressed the pe-

riod-shifting key 63, as above described. The typist usually need not hold down the shift-key 69, because it is usually automatically locked down by the shift-lock 70.

5 After the desired periods have been printed, the typist releases the shift-lock 70 in the usual manner, and proceeds to do the rest of the typing, after having actuated the returning finger-piece 58 to cause its

10 bail 61 to return the period-key 63 precisely as it returned the hyphen-shifting-key 30. The period-shifting-key 63 is provided with a forked stem 71 like the forked stem 33, thus permitting either key to be depressed

15 without interference by the other key.

When the typist desires to print a leader or row of underscore characters (which are customarily printed by the upper-case of the "6" key 10), the typist depresses an underscore-shifting-key 72, causing its forked stem 73 to swing rearwardly a rock-arm 74 fast upon a rock-shaft 75, which, like the rock-shaft 35, is journaled in the brackets 36, and which is adapted to shift the star-wheel 76 to a position overlying a C-shaped member 77, like the C-shaped members 41 and 66, but fast upon the lever 78 of the "6" key 10. This C-shaped member 77, like the C-shaped members 41 and 66, is provided with a

25 roller 42, with the result that when the crank 48 is turned, its star-wheel 76 repeatedly actuates the "6" key, and causes said key to print the underscoring characters, provided the case-shaft-key 69 has been

30 actuated as described above.

For shifting the star-wheel 76 in this manner, a cam-member 79 is provided somewhat like the cam-member 50, having an extension comprising an opening 52 and a cam-face 53, as well as a dwell 56. The connections are such that when the shaft 75 is rocked, a rock-arm 80 thereon draws forward the cam-member 79 along the face of the collar 81, and cams the star-wheel 76 to the right, to the desired position by thrusting on its hub 82 against the tension of its spring 83. The spring 83 may be like the spring 55, except that it has a less throw. The rock-arm 80 is connected to the cam-member 79 by a shouldered screw 84. The rock-arms 37 and 80 are herein illustrated as behind the usual comb 85, which serves to guide the key-levers 14, and the shafts 35 and 75 lie above the key-levers.

55 To enable the device to be readily attached to existing machines, the brackets 36 and 60 may be made fast to the outside of the frame 86 by screws 87, adapted to be threaded into suitable openings in the frame. In order to hold the brackets steady, each one has a turned-over face 88, which is provided with two screw-holes 89, so that it may receive two of the screws 87.

In order to minimize the likelihood of

60 interference of the C-shaped arm 41 with

the adjacent arm 66, the arms may be fast upon the outer opposite sides of their respective key-levers.

Each shifting key 30, 63 and 72 may slide in a guide sleeve 90 projecting rearwardly from the plate 31, and be provided with a collar 91, to limit its forward throw at the actuation of the finger-piece 58. The shafts 35 and 75 may be journaled in turned-over ends 92 of the brackets 36, and be held against sliding therein by headed screws 93 threaded into the ends of the shafts and having heads overlying the ends 92.

In order to make sure that the star-wheels 38, 76, are in such a position that the rolls 42 will slip into them in the manner described above, there is provided fast on the shaft 39 a detent star-wheel 94, which is normally held by a detent 95 in such position that the star-wheels 38, 76, are properly positioned. In order to enable the crank-handle 48 to rotate the shaft 39 and its star-wheels without interference from the detent 95, said detent is formed as the end of a depending extension 96 fast to the bail 61, the connections being such that whenever the finger-piece 58 stands in its Figure 6 position the detent 95 is effective on the star-wheel 94. The connections are such, however, that when any one of the shifting-keys 30, 63 or 72 is actuated, the swinging of the bail 61 thereby carries the detent 95 clear of the star-wheel 94 and permits it and its shaft 39 to rotate freely. To make sure that the detent 95 brings the shaft 39 to the proper position, it is provided with camming faces 97 which are adapted to enter between the teeth of the star-wheel 94 and cam it to the proper position.

Variations may be resorted to within the scope of the invention, and portions of the improvements may be used without others.

Having thus described my invention, I claim:

1. In a typewriting machine, in combination, a plurality of leader-types, leader-type-actuating keys, means operable continuously for actuating any one of said leader-types repetitiously to type a leader across a work-sheet, but normally ineffective therefore, and selecting means settable at will, independently of the leader-type-actuating keys, to render said actuating means effective to operate a selected type.

2. In a typewriting machine, the combination with a plurality of type-operating key-levers, of a shaft adjacent said levers and normally at rest, an operating arm fast on one of said levers, and an interponent normally clear of said arm but adapted to be shifted to enable the shaft when rotated to operate the key-lever.

3. In a typewriting machine, the combi-

- nation with a plurality of type-operating key-levers, of a shaft adjacent said levers, a plurality of star wheels on said shaft adapted to actuate said levers, means normally holding said wheels clear of the levers in ineffective positions, and means for selectively moving said wheels to effective positions, to enable them to selectively actuate their levers at the rotation of the shaft.
10. 4. In a typewriting machine, the combination with a type-operating key-lever, of a shaft adjacent said lever, a star wheel adjacent said lever, an extension of said lever adapted to be struck by the teeth of said wheel to actuate the key-lever, a spring normally holding the wheel clear of the extension, and a finger-piece depressible to move the wheel to effective position against the tension of the spring.
20. 5. In a typewriting machine, the combination with a type-operating key-lever, of a shaft adjacent said lever, a star wheel adjacent said lever, an extension of said lever adapted to be struck by the teeth of said wheel to actuate the key-lever, a spring normally holding the wheel clear of the extension, a cam adapted to be slid on said shaft to move the wheel to effective position against the tension of the spring, a dwell on the cam adapted to hold the wheel in its shifted position, and a finger-piece depressible to actuate the cam.
30. 6. In a typewriting machine, the combination with a plurality of type-operating key-levers, of a shaft adjacent said levers, a star wheel adjacent said levers, an extension of each of said levers adapted to be struck by the teeth of said wheel to actuate the key-lever, a spring normally holding the wheel clear of the extensions, a cam adapted to slide on said shaft, and a plurality of dwells on said cam to enable the wheel to be arrested at either of a plurality of positions, to enable it to co-operate with either of the key-levers.
40. 7. In a typewriting machine, the combination with a plurality of type-operating key-levers, of a shaft adjacent said levers, star wheels upon said shaft adapted to operate various key-levers, means holding said wheels at normally ineffective positions, and means for selectively moving a star wheel to enable it to operate either of a plurality of said levers.
50. 8. In a typewriting machine, the combination with a plurality of type-operating key-levers, of a shaft adjacent said levers, star wheels upon said shaft adapted to operate various key-levers, means holding said wheels at normally ineffective positions, a plurality of shafts parallel to the first-named shaft, shifting devices for said wheels upon said plurality of shafts, and finger-pieces for individually rotating said plurality of shafts to individually shift said wheels.
55. 9. In a typewriting machine, the combination with a plurality of type-operating key-levers, of a shaft adjacent said levers, star wheels upon said shaft adapted to operate various key-levers, means holding said wheels at normally ineffective positions, a plurality of shafts parallel to the first-named shaft, shifting devices for said wheels upon said plurality of shafts, finger-pieces for individually rotating said plurality of shafts to individually shift said wheels, and connections whereby a plurality of said finger-pieces variably rotate a shaft to enable a single wheel to selectively actuate any of a plurality of key-levers.
10. 10. In a typewriting machine, the combination with type-operating key-levers, of a transverse shaft adjacent said levers, operating cams shiftable along said shaft from normally ineffective positions to effective positions, a cam member slidable transversely of the shaft, adapted to cam an operating cam to effective position, and a finger-piece for operating said cam member.
20. 11. In a typewriting machine, the combination with type-operating key-levers, of a transverse shaft adjacent said levers, operating cams shiftable along said shaft from normally ineffective positions to effective positions, a cam member slidable transversely of the shaft, adapted to cam an operating cam to effective position, and slidable to another position to cam an operating cam to a second effective position, and separate finger-pieces adapted to selectively move the cam member to either position.
30. 12. In a typewriting machine, the combination with type-operating key-levers, of a transverse shaft adjacent said levers, operating cams shiftable along said shaft from normally ineffective positions to effective positions, a cam member slidable transversely of the shaft, adapted to cam an operating cam to effective position, an extension of the cam member engaging the transverse shaft for support, a second transverse shaft, an arm fast on the second transverse shaft connected to shift the cam member and support it, and means for rocking the second shaft to shift the cam member.
40. 13. In a typewriting machine, the combination with a plurality of type-operating key-levers, of a shaft transverse to said levers, camming devices on the shaft for operating the levers, means normally holding said devices in ineffective positions, a second shaft for making said devices effective, and a plurality of shifting keys for variably rotating the second shaft to determine on which of a plurality of key-levers the first-named shaft may be effective through a device.
50. 14. In a typewriting machine, the combination with a plurality of type-operating key-levers, of a transverse shaft beneath said

levers, a plurality of star wheels on said shaft, a C-shaped extension on each of said levers, means for separately shifting said wheels on said shaft from a normally ineffective position to an effective position to engage the teeth of a wheel with an extension, and means for rotating the shaft to actuate its lever by the wheel.

15. In a typewriting machine, the combination with a plurality of type-operating key-levers, of a transverse shaft beneath said levers, a star wheel on said shaft, an extension of one lever extending below said shaft and adapted to engage between the teeth of the wheel, and means for rotating the shaft to operate the lever.

16. In a typewriting machine, the combination with a plurality of type-operating key-levers, of normally ineffective means for each lever for repeatedly operating it, a shifting key for each lever adapted to make its means effective, connections for holding said means effective when made effective by its key, and a finger-piece universal to said 25 means for making them ineffective.

17. In a typewriting machine, the combination with a plurality of type-operating levers, of a transverse shaft, separate means connected to said shaft for operating each 30 type lever by the shaft, a plurality of secondary shafts, cam members moved by said secondary shafts individually controlling the separate means, rock arms for separately operating the secondary shafts, shifting keys 35 for the rock arms, a bail universal to the rock arms for returning to normal position any means, and a finger-piece for actuating the bail.

18. In a typewriting machine, the combination with a plurality of type-operating keys, of a shaft for operating said keys, normally ineffective devices whereby the shaft operates the keys, means for differentially positioning one of said devices to determine which key it shall operate, a rock shaft for so positioning it, a plurality of rock arms on the rock shaft, and shifting keys having a substantially identical throw and operating upon said rock arms at different distances from their rock shaft to vary its operation to differentially position the device controlled by it.

19. In a typewriting machine, the combination with a plurality of type-operating keys, of a shaft for operating said keys, normally ineffective devices whereby the shaft operates the keys, means for differentially positioning one of said devices to determine which key it shall operate, a rock shaft for so positioning it, a plurality of rock arms on the rock shaft, shifting keys having a substantially identical throw and operating upon said rock arms at different distances from their rock shaft to vary its operation to differentially position the

device controlled by it, connections whereby any device remains positioned when moved by its rock arm, and a bail universal to said rock arms adapted to be operated to return the rock arms.

20. In a typewriting machine, the combination with a plurality of type-operating keys, of a shaft, a star wheel slidably splined to the shaft to be shifted from an ineffective position to a position where it can operate 75 a key, a spring encircling said shaft to normally hold it ineffective, and a cam member adapted to be shifted transversely of the shaft to shift the star wheel.

21. In a typewriting machine, in combination, a plurality of leader-types, leader-type-actuating keys, means for actuating any one of said leader-types repetitiously to type a leader across a work-sheet, but normally ineffective therefor, and selecting means settable at will to render said actuating means effective to operate a selected type, said selecting means comprising a selector-key for each of said types.

22. In a typewriting machine, the combination with a plurality of type-operating key-levers, of a shaft, means for rotating said shaft, means on said shaft to actuate said key-levers repeatedly when said shaft is rotated, and means on said machine settable at will to position the actuating means on said shaft selectively to operate any of said key-levers.

23. In a typewriting machine, the combination with a plurality of type-operating key-levers having extensions fixed thereto, of a shaft, means for rotating said shaft, means on said shaft adapted to engage said extensions to actuate said key-levers repeatedly when said shaft is rotated, and means 105 on said machine settable at will to position the actuating means on said shaft selectively to engage any of said extensions to operate the corresponding key-lever.

24. In a typewriting machine, the combination with a plurality of type-operating key-levers, of a shaft adjacent said levers, means for rotating said shaft, a plurality of means on said shaft adapted to actuate said levers repeatedly when said shaft is rotated, 110 means normally holding said plurality of actuating means in ineffective position, and means on said machine settable at will to render any of said actuating means effective to operate the corresponding key-lever.

25. In a typewriting machine, the combination with a plurality of type-operating key-levers having extensions fixed thereto, of a shaft adjacent said levers, means for rotating said shaft, a plurality of star-wheels on said shaft adapted to engage said extensions to actuate said levers repeatedly when said shaft is rotated, means normally holding said wheels in ineffective position clear of the extensions on said levers, means 125 130

for selectively moving said wheels to effective position in engagement with said extensions to operate any desired lever, and means adapted to engage said shaft when said wheels are in ineffective position to properly position the shaft to enable the star-wheels fixed thereto to engage said extensions without encountering obstructions.

26. In a typewriting machine, the combination with a plurality of type-operating key-levers having extensions fixed thereto, of a shaft adjacent said levers, means for rotating said shaft, a plurality of star-wheels on said shaft adapted to engage said extensions to actuate said levers repeatedly when said shaft is rotated, means normally holding said wheels in ineffective position clear of the extensions on said levers, means for selectively moving said wheels to effective position in engagement with said extensions to operate any desired lever, and means adapted to engage said shaft when said wheels are in ineffective position to properly position the shaft to enable the star-wheels fixed thereto to engage said extensions without encountering obstruc-

tions, said last-named means comprising an additional star-wheel fixed to said shaft and a detent pivoted on said machine and adapted to engage said additional star-wheel.

27. In a typewriting machine, in combination, leader-types, leader-type actuating keys, and means for actuating any one of said leader-types repetitiously to type a leader across a work-sheet, said actuating means comprising a shaft, star-wheels, one for each key-lever, mounted on said shaft to rotate therewith, arms, one on each of said key-levers, to be engaged by the corresponding star-wheels and operated thereby, each of said arms and the associated star-wheel being normally disconnected, and selecting means, independent of the leader-type-actuating keys, to effect an operative connection between any one of said arms and the corresponding star-wheel.

ARTHUR E. HOWELL.
